UNITED STATES PATENT OFFICE.

THOMAS HANSEN TOMBYLL, OF MONTREAL, QUEBEC, CANADA.

DECORTICATING-MACHINE.

1,064,029.

Specification of Letters Patent.

Patented June 10, 1913.

Application filed July 27, 1908. Serial No. 445,661.

To all whom it may concern:

Be it known that I, THOMAS HANSEN TOMBYLL, of the city of Montreal, Province of Quebec, Canada, have invented certain new and useful Improvements in Decorticating-Machines; and I do hereby declare that the following is a full, clear, and exact description of the same.

My invention relates particularly to the type of decorticating machines disclosed in Letters Patent No. 882,766 granted March 24, 1908 to Thomas Edward Mitchell and Thomas Hansen Tembyll and it has for its object to increase the efficiency of machines of this type.

The invention speaking generally consists in means for causing the straw to buckle while passing through the machine for the purpose of causing the same to spread and the fibers to separate thereby liberating the woody matter; and it further consists in the combination with a group of corrugated rolls and a pair of drawing and scraping webs, of a hackling roller located between such group and pair. For full comprehension, however, of my invention reference must be had to the accompanying drawing in which a section of a decorticating machine is illustrated with my invention applied thereto.

The fluted rollers are in vertical pairs *b*, *b*, *c*, *c*, and *d*, *d*, indicated by dotted lines, and the ends *e* thereof protrude through and find bearing in housings bolted to the machine frame one only of which being shown at *f*. Springs *g* keep the bearing blocks *h* in their proper positions.

Heretofore it has been the practice to cause the straw to be under tension while passing through this group of fluted rollers to secure a drawing action in addition to the crushing action, but I have discovered that by buckling the straw each stem spreads and the fibers thereof are separated from each other. To this end I cause the rollers *c*, *c*, to travel at a slightly greater speed than the rollers *b*, *b*, and the rollers *d*, *d* to travel at a slightly greater speed than the rollers *c*, *c*, by utilizing different sized gears *k*, *l*, and *m* to drive the rollers such gears being of increasing diameter, the gear *k* the smallest and the gear *m* the largest of the series. They are separated from each other and a pair of intermediate pinions *n* and *o*, respectively, operatively connect them together, thus causing rotation imparted to the lower-

most roller *c* to be imparted to the other lowermost rollers of the group the speed of travel decreasing from the pair of rollers *d*, *d* which first receive the flax to the pair *b*, *b* which deliver the straw from this group, the difference in speed between the rollers *b*, *b* and *c*, *c* being less than between *c*, *c* and *d*, *d*. The effect is that during the passage of the flax through this group of rollers, it is buckled and the ribbons into which the cortex is longitudinally split by the action of the fluted rollers are caused to swell out or balloon by the axial compression to which the buckling action subjects the cortex, thereby freeing the broken woody matter and allowing it to fall, while the hackling roller picks up the cortices lightly and carries them over to the group of fluted rollers by which they are caught and drawn down over the pins of the hackling roller thereby effectively separating the ribbons and precipitating the broken woody matter.

The hackling rollers are preferably disposed with their surfaces above the level of the feeding surfaces of the webs and fluted rollers.

The drawing and scraping webs are indicated at *p* and *q* and between each pair of these webs and the group of fluted buckling rollers I locate a hackling roller *r*.

It is to be understood that in the machine illustrated in the drawings the flax passes through the machine from right to left.

These members are so driven that the first pair of drawing webs will have a comparatively low speed, the hackling roller (next to act upon the flax) has a slightly higher speed, the group of rollers a still higher speed, the next pair of webs a still higher, and so on throughout the series.

Operation: It is to be understood that if necessary any number of groups of fluted rollers interspersed with drawing webs and hackling rollers, may be utilized but it is only necessary to show a single series to illustrate the different actions to which the flax is subjected and I will now describe the actions in the order of their succession.

The invention, as before pointed out, relates to improvements in machines such as illustrated in United States Patent No. 882,766 and the operation of the present machine, which will be more readily understood from a reference to this patent, is as follows: The flax travels from right to left of the figure of the drawing, being first

thrown upon a conveyer or endless apron and carried thereby, after a primary breaking up action, as described and illustrated in the above mentioned patent, to the scraping, drawing and straightening webs *p* which subject the flax to a compression and partially clean it of the woody matter and loosen the fibers from each other to a certain extent. As the mass is expelled from the webs *p* it is received by a hackling roller *r* and is passed thereby to the first pair of fluted rollers *d* of the group and as such rollers *d* rotate at a slightly greater speed than the hackling roller, the flax is drawn over the points of the latter, which, penetrating the fibers, split the same longitudinally with a raking action so as to release the inner woody matter contained in the separate strands. The mass passes from the rollers *d* to the second pair *c* and as these latter rotate at a slightly slower speed than the pair *d* the mass will buckle between the two pairs and so augment the division thereof into long fine fibers and simultaneously precipitate the loose woody matter.

The mass is subjected to another buckling action as it passes from the rollers *c* to the last pair of rollers *b* because these latter rotate more slowly than the pair *c*. The flax is received from the rollers *b* by second webs *q* which travel at a greater speed than the rollers *b* and thereby stretch the mass and compress, scrape and draw out the flax to further relieve it of the woody matter.

The best result is obtained by having less difference in speed between the second and third pair of rolls than between the first and second, the effect being that the flax will buckle to a different degree at these points.

What I claim is as follows:—

1. In a decorticating machine the com-

bination with a pair of drawing webs and a series of pairs of fluted rollers, of a hackling roller located between the said drawing webs and fluted rollers, said hackling roller being adapted to receive the flax directly from the drawing webs and deliver it to the fluted rollers, of means for rotating the pair of fluted rollers first receiving the flax at a greater speed than the second pair of fluted rollers and for rotating the third pair of fluted rollers at a lesser speed than the said second pair the difference in speed between the first and the second pairs of fluted rollers being greater than the difference of speed between the second and third pairs. 45 50 55

2. In a decorticating apparatus in combination a pair of drawing webs, a series of pairs of fluted rollers, a hackling roller located between the drawing webs and the fluted rollers and adapted to receive the flax from the drawing webs and to deliver it to the fluted rollers, means for imparting a greater speed to the hackling roller than to the drawing webs and a greater speed to the fluted rollers than to the hackling roller, and means for rotating the second pair of fluted rollers at a lesser speed than the first pair and also for rotating the third pair of 60 65 70 75 the said fluted rollers at a lesser speed than the second pair, the difference in the speed between the first and the second pairs of said fluted rollers being greater than the difference in speed between the second and third pairs.

In testimony whereof, I have signed my name to this specification, in the presence of two subscribing witnesses.

THOMAS HANSEN TOMBYLL.
